United States Patent Office

Des. 196,155
Patented Aug. 27, 1963

196,155

SLIDE PROJECTOR

Paul A. Hoogesteger, Brighton, and Jacob W. Patla,
Rochester, N.Y., assignors to Bausch & Lomb Incorporated,
Rochester, N.Y., a corporation of New York

Filed Nov. 28, 1962, Ser. No. 72,635

Term of patent 14 years

(Cl. D61—1)

FIG. 1 is a top plan view of a slide projector showing our new design; the bottom being substantially identical thereto;

FIG. 2 is a side view thereof;

FIG. 3 is a front view thereof; a portion being broken away for convenience of illustration; and

FIG. 4 is a rear perspective view thereof.

We claim:

The ornamental design of a slide projector, substantially as shown and described.
